[57] CLAIM

The ornamental design for a “cordless telephone,” as shown and described.

DESCRIPTION

FIG. 1 is a top, front and right side perspective view of a cordless telephone according to our design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a top, front and right side perspective view of a cordless telephone base unit according to our design;

FIG. 9 is a top plan view thereof;

FIG. 10 is a front elevational view thereof;

FIG. 11 is a right side elevational view thereof;

FIG. 12 is a rear elevational view thereof;

FIG. 13 is a left side elevational view thereof;

FIG. 14 is a bottom plan view thereof;

FIG. 15 is a top, front and right side perspective view of a cordless telephone handset according to our design;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof; and,

FIG. 21 is a bottom plan view thereof.

The cordless telephone base unit and handset have been shown separately in FIGS. 8-14 and 15-21 respectively for convenience of illustration.
